(57) **CLAIM**

The ornamental design for a storage container, as shown and described.

DESCRIPTION

FIG. 1 is a front right perspective view of a storage container;

FIG. 2 is a front left perspective view thereof;

FIG. 3 is a front planar view thereof;

FIG. 4 is a rear planar view thereof;

FIG. 5 is a top view thereof;

FIG. 6 is a bottom view thereof;

FIG. 7 is a right side view thereof;

FIG. 8 is a left side view thereof;

FIG. 9 is a front right perspective view of a second embodiment of a storage container;

FIG. 10 is a front left perspective view thereof;

FIG. 11 is a rear planar view thereof;

FIG. 12 is a front planar view thereof;

FIG. 13 is a top view thereof;

FIG. 14 is a bottom view thereof;

FIG. 15 is a right side view thereof; and,

FIG. 16 is a left side view thereof.

The lines shown in phantom are for illustrative purposes only and do not form part of the invention.

The broken line portions of the disclosure are for illustrative purposes only and forms no part of the claimed design.
